UNITED STATES PATENT OFFICE.

WALTER LOSCH, OF TOPTON, PENNSYLVANIA.

CUTTING-TOOL.

1,195,826.

Specification of Letters Patent. Patented Aug. 22, 1916.

Application filed April 25, 1914. Serial No. 834,501.

To all whom it may concern:

Be it known that I, WALTER LOSCH, citizen of the United States, residing at Top-ton, in the county of Berks and State of 5 Pennsylvania, have invented certain new and useful Improvements in Cutting-Tools, of which the following is a specification.

My invention relates to improvements in cutting tools, the same being particularly 10 adapted for use in connection with a lathe or the like, for cutting and trimming the metal pipes, bars, rods, etc. carried thereby.

As its primary object, the tool contemplates a structure, such in its nature, as to 15 first firmly grasp and hold the material acted upon against radial play, and secondly, to cut or trim the said material as it is turned or moved by the lathe; the cutting operation being effected through manipulation of a suitable lever, so connected to 20 the cutting blades or knives as to render the latter operative or otherwise as occasion may demand.

The above and additional objects are 25 accomplished by such means as are illustrated in their preferred embodiment in the accompanying drawings, described in the following specification and then more particularly pointed out in the claims which are 30 appended hereto and form a part of this application.

In describing my invention in detail reference will be had to the accompanying drawings wherein like characters denote like 35 or corresponding parts throughout the several views, and in which;—

Figure 1 is a front elevation of a cutting tool constructed in accordance with the present invention; Fig. 2 is a side elevation, the 40 operating lever being partly broken away; Fig. 3 is an enlarged elevation of one of the cutting blades and its support; Fig. 4 is a section on the line 4—4 of Fig. 3; Fig. 5 is a top plan view of the adjusting lever 45 and its support; Fig. 6 is a fragmentary view illustrating the manner in which the operating lever is attached to the frame or body of the tool; and Fig. 7 is a perspective view of the clamp.

Referring now to the drawings by numerals, 1 designates the frame or body of the tool, the said frame having an extension 2 integral therewith, the latter being attachable, in any suitable manner, to the 55 lathe (not shown) in connection with which the tool is adapted to be used. An exten-

sion 3 is integral with the tool frame 1 at its uppermost end, the said extension in turn being provided with a semi-circular plate like enlargement 4 over the top face 60 of which an adjusting lever 5 is operated, said adjusting lever being mounted upon a suitable shaft 6 extending vertically through the extension 3, said shaft being rotatable, through movement of said lever to operate 65 a pinion 7 mounted thereupon in a manner apparent upon reference to Fig. 2.

As a means whereby the adjusting lever 5 may be locked in the desired adjusted position, I provide a suitable clamp 8 enlarged at one end as indicated at 9, the enlargement being engageable with the under face of the lever 5 and the clamp proper being engageable with the under face of the plate like enlargement 4 of the frame. 70 A bolt 10 is screw threaded into the said clamp 8, the lever 5, and an auxiliary lever 11, the latter being rotatable in a plane above the said lever 5 to move the said clamp into and out of firm frictional 75 engagement with the enlargement 4, the purpose of which is obvious.

An arm 12 in the form of a segment and having teeth 13 is mounted for oscillation about a pivot pin or bolt 14 carried by the 80 frame, said arm being integral with a sleeve or collar 15 through which the pin extends, the said sleeve serving as a means whereby a second segmental arm 16 also provided with teeth 17 is held in spaced relation to 90 the arm 12 aforesaid, the said last mentioned arm being also oscillatable upon the pin 14, the latter extending therethrough. Gripping jaws 18 and 19 are integral respectively with the sleeve 15 and the arm 95 16, said jaws being movable toward and from each other through actuation of pinion 7. Said pinion 7 being in mesh with the teeth 13 of arm 12 and the teeth 17 of arm 16, it is apparent that the said two 100 jaws 18 and 19 will be oscillated about the pivot pin 14 and made to move in a manner necessary to operation through movement of lever 5, the latter being mounted upon the shaft 3 to which the pinion 7 is 105 secured. The said frame 1 at its lowermost end is laterally extended as at 20, the said extension being shaped to receive a complementary tool holding device 21, said device being angularly grooved to receive a 110 blade or knife 22. A suitable locking pin 23 is carried by said device 21 to lock the

blade immovable relatively to the device yet slideable relatively to the extension 20 of the frame.

Upon the opposite side of the tool frame 1 from that upon which the extension 20 is formed, the said frame is laterally extended as at 24, the said extension 24 being also formed to receive a tool holding device 25, so arranged relatively to the extension 24, as to clamp within a second angular groove a second blade or knife 26. A pin 27 is operable within said block 25 to lock the blade 26 immovable relatively thereto. Plates 28 are secured to each of the extensions 20 and 24 to form guides for the tool holding devices 21 and 25 whereby the said devices with the blades 22 and 26 attached thereto may be slid relatively to the frame in a manner to be hereinafter fully described.

As a means whereby the blades 22 and 26 may be moved relatively to each other, I provide an operating lever 29, said lever carrying at its lowermost end a pin 30 operating within an opening therefor in the device 21. At a point adjacent the said pin 30 the lever 29 is fulcrumed, said fulcrum being effected by means of a pin 31 passing through the said lever, the pin being carried by a link 32 pivoted as at 33 to the frame 1 in a manner apparent upon reference to Fig. 6. Above the fulcrum point formed by pin 31, operating lever 29 has attached thereto an arm 34, said arm being pivoted as at 35 to device 25 at one end and as at 36 to the lever, this arrangement, upon operation of the said lever, causing the said two devices and the blades carried thereby to be moved relatively to each other in a cutting operation.

Operation of the tool is as follows: The extension 2 is so attached to the lathe machine as to position the center of the cutting tool, as indicated at A in the center line of the lathe, the metal rod or tube acted upon being then clamped between the jaws 18 and 19 of the cutting tool, the latter holding the said rod or pipe incapable of radial play. Said rod or bar having been set, and the jaws 18 and 19 locked through operation of auxiliary lever 11 and adjusting lever 5, operating lever 29 is depressed, causing blades 22 and 26 to move toward each other. As the said pipe or bar is rotated by the lathe, the cutting edges of the blades 22 and 26 bite into and cut the said material and, by continued pressure upon operating lever 29 cause the said blades to move into the position indicated in Fig. 1, in which event, the material acted upon is severed or cut as desired.

From the foregoing, taken in connection with the accompanying drawings it is apparent that operation of lever 29 will slide tool holding devices 21 and 25 within their

respective supports and relatively to each other; that the material acted upon is held fast, or against movement other than rotary, by clamping jaws 18 and 19; and that materials varying in size may be acted upon by the cutting tool, adjustment of the various parts of the tool being effected in a manner apparent upon reference to the drawings.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:—

1. In a cutting tool, blades movable into and out of engaging proximity in a cutting operation, and means oscillatable from a fixed axis to hold the material acted on for rotation and against radial play.

2. In a cutting tool, relatively movable jaws having a fixed axis of oscillation, each jaw being provided with a gear sector, an engaging pinion turnable to move said jaws during adjustment, said jaws being engageable with the material to be cut for holding said material against radial play, means to lock the adjusting means against movement subsequent to adjustment, and cutting means operable in proximity to the mentioned jaws.

3. In a cutting tool, a frame, relatively movable jaws having a fixed axis of oscillation upon the frame, each jaw being provided with a gear sector and engaging pinion turnable to move said jaws with the pinion, a semicircular guiding plate on the frame, a clamp member mounted on the lever and engageable upon the plate to secure the lever and consequently the jaws against movement subsequent to adjustment, and cutting means operable in proximity to the said jaws.

4. In a cutting tool, a frame, jaws mounted for oscillation upon the frame and movable relatively to engage the work therebetween each having a sector, a pinion engaging both sectors to oscillate the jaws, a semi-circular guiding plate formed on the frame, a lever movable with the pinion, a clamp on the lever for engaging the plate to retain said lever in its adjusted position, and cutting means operable in proximity to the said jaws.

5. A cutting tool including a frame, relatively movable jaws mounted thereon for lightly engaging the work, relatively mov-

able holding devices provided with cutting tools and adapted to move the tools across the jaw space, a lever fulcrumed to the frame, and means connecting the lever at 5 opposite sides of its fulcrum with each of the devices.

6. A cutting tool including a frame, relatively movable jaws mounted thereon adapted to lightly engage the work, relatively 10 movable tool holding devices mounted in the frame, provided with tools and adapted to move said tools diametrically across the jaw space, a lever fulcrumed on the frame, and links forming a connection between the lever 15 at opposite sides of its fulcrum and to each of the devices.

7. A cutting tool including a frame, relatively movable jaws movable thereon for lightly engaging the work, tool holding devices mounted on the frame, having cutting tools adapted to move the points thereof diametrically across the jaw space and to mutually engage at the central axis of said 25 jaw space, a lever fulcrumed to the frame, and links connecting the lever at opposite sides of its fulcrum to each of the devices for equally distributing the power applied to said devices.

8. A cutting tool including a frame, provided with oppositely disposed extensions, 30

with guides provided on the extensions, jaws mounted on the frame and adapted to lightly engage the work disposable between the extensions, tool holding devices movable in the guides provided with tools and adapted by 35 said movement to direct the tools diametrically across the jaw space, a lever fulcrumed on the frame, and links pivotally connecting the lever at opposite sides of the fulcrum thereof to each of the devices.

9. A cutting tool including a frame provided with oppositely disposed spaced extensions, guides on the extensions, tool holding devices movable in the guides in parallel directions, or out of alinement, tools adjustably mounted in the devices and adapted to be moved across the jaw space to come to rest with the points of said tools in engagement at the axis of the jaw space, the tools being in alinement at that time, a lever fulcrumed on the frame, and links pivotally connecting opposite sides of the lever with each of the devices.

In testimony whereof I affix my signature in presence of two witnesses.

WALTER LOSCH.
